UNITED STATES PATENT OFFICE.

ANDREW G. PAUL, OF BOSTON, MASSACHUSETTS, ASSIGNOR TO PAKIN COMPANY, A CORPORATION OF NEW YORK.

HEATING SYSTEM.

No. 823,074.

Specification of Letters Patent.

Patented June 12, 1906.

Application filed April 16, 1901. Serial No. 56,058.

To all whom it may concern:

Be it known that I, ANDREW G. PAUL, a citizen of the United States, residing in Boston, in the county of Suffolk and State of Massachusetts, have invented a new and useful Improvement in Radiator Attachments for Heating Systems, of which the following is a full, clear, and exact specification, reference being had to the accompanying drawings, which form a part hereof.

This invention relates to a radiator attachment for a heating system wherein steam or other suitable heating agent is circulated for the purpose of conveying and imparting heat to the places desired; and it consists in an improved construction and arrangement of the discharge or outlet valve in such a system.

The object of my invention is to positively control the discharge of the air and the water of condensation from the radiator, and thus to improve and increase the efficiency of the system, and at the same time to prevent the loss or waste of the heating-vehicle through the discharge-pipe, thus securing economy of operation.

My invention consists in a radiator attachment for use in heating systems consisting of a discharge-valve device comprising a suitable valve-casing provided with a port for the discharge of the water, a fluid-pressure motor controlling said port, the casing being provided with a fluid-pressure chamber on one side of the motor, an air-passage extending through the motor, a valve-piece adapted to close the air-passage, and a float adapted to slide on the valve-piece and to operate the same.

My invention also consists in certain other features of construction and combinations of parts hereinafter described and claimed.

My invention is fully illustrated in the accompanying drawings, in which—

Figure 1 shows my invention as applied to a system containing two radiators. Fig. 2 is a vertical sectional view of the preferred form of my discharge-valve device. Fig. 3 shows my invention applied to a system embodying two radiators and in which the air-passage leading from one of the radiators is controlled by a thermostat adapted to be placed upon the wall of the room or in any other suitable position, and the other air-passage is con-

trolled by a thermostat placed in the air-passage itself.

Similar numbers denote similar parts in the different figures.

Referring to Fig. 1, 1 1 are radiators of any suitable construction. 2 is the supply-pipe. 3 3 are supply-valves. 4 4 are the discharge-valve devices. 5 is the common discharge-pipe having branches connecting with each discharge-valve device. 28 is a pump of any suitable construction which is connected with the lower end of the discharge-pipe.

In Fig. 2 I have shown the construction of the discharge-valve device. 14 is the pipe or passage leading to the discharge-valve device. 15 is the valve-casing, which may be made in any suitable form. This casing is provided with a port 16, through which the water of condensation escapes. 17 is a valve which is adapted to close the port 16. 18 is a fluid-pressure motor in the form of a piston, which is made to properly fit the valve-casing and which is adapted to control the port 16 in any suitable manner. The piston is provided with a stem, which carries the valve 17 at its lower end. When the piston rises and falls, the valve 17 is lifted or lowered by means of this stem. 20 is a fluid-pressure chamber which is formed in the upper part of the valve-casing above the piston 18. 21 is a passage for the escape of air or steam or vapor. This air-passage serves as a communication between the fluid-pressure chamber 20 and the inlet or the supply side of the valve device or in the particular form shown in this figure with the valve-chamber, which is on the other side of the piston from the fluid-pressure chamber 20. A spring is employed which is adapted to bear down upon the upper side of the piston 18, thus tending to force the piston down to close the port 16.

25 is a float-valve which is adapted to be operated by the water of condensation collecting in the lower part of the valve-chamber and to control the air-passage 21. In the particular form shown in Fig. 2 the float-valve is in the form of a ball-valve provided with a central passage or opening, through which the stem of the piston extends. 26 is a pipe or passage connecting the fluid-pressure chamber with the discharge-pipe 5. The

pipe or passage 26 is provided with a valve 27, by means of which the said pipe can be controlled. A sleeve 29 is provided which is adapted to be moved back and forth on the piston-stem by the float 25, so as to cause the said sleeve to open or close the air-passage 21, which extends through the piston. The sleeve or valve-piece 29 is provided at its ends with collars 30, against which the float 25 is adapted to strike. When the sleeve 29 is in its highest position, the upper collar 30 acts as a valve and closes the end of the air-passage 21. The float 25 slides upon the sleeve 29. When the parts are in the position shown in Fig. 2, the air is drawn out through the air-passage 21, the fluid-pressure chamber 20, the passage 26, and the discharge-pipe 5 by the pump 28. When the water of condensation collects in the valve, the float 25 is lifted until it strikes the upper collar 30 of the sleeve 29. The float thereupon lifts the sleeve until the upper collar 30 is pressed against the piston, so as to close the air-passage 21. As a result of this, differential pressures are produced on the two sides of the piston to such an extent as to cause the piston to be lifted, thereby opening the discharge-port 16 and causing the water of condensation to be drawn out. As the water of condensation escapes the float 25 falls until it strikes the lower collar 30 of the sleeve 29. The float then forces the sleeve down upon the piston-stem, thereby opening the passage 21 and again equalizing the pressures on the two sides of the piston or decreasing the difference between said pressures sufficiently to cause the piston to descend and close the port 16. As a result of this construction, it will be seen that the air-passage 21 remains closed for a longer period of time than if the air-passage were closed directly by the float 25, as a result of which the port 16 remains open longer for the discharge of the water of condensation, thus causing larger quantities of water to be discharged at each opening of the port 16. The sleeve 29 is preferably made in two parts, as shown in Fig. 2, these two parts being provided with screw-threaded portions by means of which the two parts can be adjusted one upon the other, so as to increase or decrease the length of the sleeve 29 and to thereby regulate the opening and closing of the passage 21. Any other means may be employed for shortening or lengthening the said sleeve.

Referring to Fig. 3, 1 1 are radiators of any suitable form. 2 is a supply-pipe. 3 3 are supply-valves. 4 4 are discharge-valve devices. 5 is a common discharge-pipe. 28 is a pump connected with the lower end of the discharge-pipe. The system shown in this figure is the same as that shown in Fig. 1 in the respects already mentioned. In the discharge-valve device connected with the up-

per radiator the valve 27, which is placed in the passage or pipe 26, is controlled by means of a thermostat 31, which is placed upon the wall of the room or in any other suitable position. The connection between the thermostat 31 and the valve 27 is made in any usual manner—for example, by means of an electric circuit 32 32, including a battery 33 and an electromagnet 34 and an armature-lever 35. When the room has been heated to the desired point, the thermostat 31 operates to close the valve 27, as a result of which neither air nor water of condensation will be drawn out from the radiator, but will be allowed to collect therein, thus reducing the amount of heat given off by the radiator and tending to prevent the overheating of the room. When the temperature of the room is below the desired point, the thermostat 31 operates to open the valve 27, in which condition the air and water of condensation are drawn out from the system in the manner already explained. In the discharge-valve device connected with the lower radiator in Fig. 3 the pipe or passage 26 is made in the form of a pipe extending a short distance away from the body of the valve and provided with the ordinary thermostatic valve 36. This thermostatic valve 36 permits the escape of air through the pipe 26, but prevents the escape of steam through said pipe. The thermostatic valve 36 is put a short distance away from the main body of the valve device 4 in order that the valve 36 may be more sensitive in its operation. In other respects the system shown in Fig. 3 operates in the same manner as the system shown in Fig. 1.

It will be apparent that my invention is also applicable to a system in which no exhausting device is employed, but in which the heating-vehicle is circulated under pressure. It is also obvious that my improved heating system may be used for drying purposes.

Some of the advantages secured by my improved system are as follows: The water and air are intermittently and positively removed from the radiator or heater whenever they collect in any appreciable quantity. The water of condensation which collects operates with certainty upon the float-valve, and the opening and closing of the air-passage and the discharge-passage for the water are thus controlled and operated with certainty. The air-passage is closed by means of a valve device which shuts the said air-passage off completely and mechanically. The operation of the system is efficient and economical. By employing the thermostat to control the air-passage the wasting of the heating-vehicle is prevented. When the thermostat which controls the air-passage is placed in the room to be heated, the invention tends to prevent the overheating of said room and at the same time secures economy by prevent-

ing the use of the heating-vehicle in doing heating work which is not required.

What I claim as new, and desire to secure by Letters Patent, is—

5 1. A radiator attachment for use in heating systems consisting of a discharge-valve device comprising a suitable valve-casing provided with a port for the discharge of the water, a fluid-pressure motor controlling said 10 port, the casing being provided with a fluid-pressure chamber on one side of the motor, an air-passage extending through the fluid-pressure motor, a valve-piece adapted to close the air-passage, a float adapted to slide 15 on the valve-piece and to operate the same, substantially as set forth.

2. A radiator attachment for use in heating systems consisting of a discharge-valve device comprising a suitable valve-casing 20 provided with a port for the discharge of the water, a piston controlling said port, the casing being provided with a fluid-pressure chamber on one side of the piston, an air-passage extending through the piston, a valve- 25 piece adapted to close the air-passage, a float adapted to slide on the valve-piece and to operate the same, substantially as set forth.

3. A radiator attachment for use in heating systems consisting of a discharge-valve 30 device comprising a suitable valve-casing provided with a port for the discharge of the water, a piston controlling said port, the cas-

ing being provided with a fluid-pressure chamber on one side of the piston, an air-passage serving as a communication between the 35 fluid-pressure chamber and the system on the inlet side of the valve device, a valve-piece, and a float adapted to slide on the same and operated by the water of condensation and controlling the air-passage, and a communication 40 between the fluid-pressure chamber and the discharge-pipe, and a thermostatic device adapted to be operated by the heat of the room and to control the said communication, substantially as set forth. 45

4. A radiator attachment for use in heating systems consisting of a suitable valve-casing provided with a port for the discharge of the water, the discharge-valve 17, the piston 18 connected with the valve-stem and provided with the air-passage 21, the fluid-pressure chamber 20, the float 25, the sleeve 29 having the collars 30, the passage 26 connecting the fluid-pressure chamber with the discharge-pipe beyond the discharge-valve, 50 substantially as set forth. 55

In testimony whereof I have signed my name to this specification in the presence of two subscribing witnesses.
